US00D441654S

(12) **United States Design Patent** (10) Patent No.: **US D441,654 S**
Sayers (45) Date of Patent: ** May 8, 2001

(54) **LIQUID DISPENSER**

(75) Inventor: **Richard C. Sayers**, Perrysburg, OH (US)
(73) Assignee: **Owens-Illinois Closure Inc.**, Toledo, OH (US)
(**) Term: **14 Years**
(21) Appl. No.: **29/069,936**
(22) Filed: **Apr. 18, 1997**
(51) LOC (7) Cl. **09-07**
(52) U.S. Cl. **D9/448**
(58) Field of Search D9/300, 301, 440, D9/447, 448; 22/320, 321.1, 321.7, 321.9, 323, 324, 383.1, 385, 402.1, 402.21, 402.24, 153.13, 153.07

(57) **CLAIM**

The ornamental design for a liquid dispenser, as shown and described.

DESCRIPTION

FIG. 1 is a perspective view of the liquid dispenser showing my new design;
FIG. 2 is a side elevational view;
FIG. 3 is a top plan view;
FIG. 4 is a front elevational;
FIG. 5 is a rear elevational view;
FIG. 6 is a bottom plan view;
FIG. 7 is a fragmentary view on an enlarged scale of a portion of the liquid dispenser shown in FIG. 4;
FIG. 8 is a perspective view of a modified form of liquid dispenser showing my new design;
FIG. 9 is a side elevational view;
FIG. 10 is a top plan view;
FIG. 11 is a front elevational;
FIG. 12 is a rear elevational view;
FIG. 13 is a bottom plan view;
FIG. 14 is a perspective view of another modified form of liquid dispenser showing my new design;
FIG. 15 is a side elevational view;
FIG. 16 is a top plan view;
FIG. 17 is a front elevational;
FIG. 18 is a rear elevational view;
FIG. 19 is a bottom plan view;
FIG. 20 is a perspective view of another form of liquid dispenser showing my new design;
FIG. 21 is a side elevational view;
FIG. 22 is a top plan view;
FIG. 23 is a front elevational;
FIG. 24 is a rear elevational view; and,
FIG. 25 is a bottom plan view.
